Patented July 23, 1918.

By Mason Farnick Lawrence,
Attorneys

UNITED STATES PATENT OFFICE.

SOLOMON E. AARON, OF BOSTON, MASSACHUSETTS.

PLIERS.

1,273,713.

Specification of Letters Patent. Patented July 23, 1918.

Application filed August 24, 1917. Serial No. 188,026.

To all whom it may concern:

Be it known that I, SOLOMON E. AARON, a citizen of the United States, residing at Boston, in the county of Suffolk and State 5 of Massachusetts, have invented certain new and useful Improvements in Pliers; and I do hereby declare the following to be a full, clear, and exact description of the invention, such as will enable others skilled 10 in the art to which it appertains to make and use the same.

This invention relates to hand tools, and more particularly to a type of tools designed for use by electricians and others, to facilitate the removal of insulation from various 15 kinds of insulated electrical wire.

It is one of the objects of the present invention to provide for the removal with facility and the least possible injury to the 20 metallic member of the wire, of the insulation therefrom and especially provide for the facilitation of the removal of insulation from the twin wires both of a round type and a flat type.

Electricians frequently have, in the practice of their occupation, to remove insulation from twin wires of different type, one form of this wire having the insulation of 25 transverse section of which is circular, while in the other form of the wire the transverse section is more or less elliptical so that the insulation assumes a relatively 30 flat form.

It is therefore a feature of my invention 35 to provide a pair of pliers with means for removing accurately, rapidly and thoroughly the insulation from either round twin wire or flat twin wire, and for the accomplishment of this object, I provide a tool 40 having on each opposite side a pair of cutting blades disposed so as to more efficiently secure the desired object.

A further object of my invention is to improve the construction of pliers having 45 means for stripping and removing the insulation from electrical conductors and particularly to provide such a tool in which the splitting and stripping means are so arranged that strength of parts is obtained 50 and at the same time a tool is provided which is neat and attractive in appearance and which will pack readily in a kit and

the blades of which may be readily renewed or removed for sharpening which may be required.

With the above object in view the invention consists in the combination of the parts, construction, and in details of construction, as will be more fully hereinafter described, the invention being illustrated in various 60 embodiments in the accompanying drawing wherein:

Figure 1 is a side elevation of the improved pliers looking at the side of the tool provided with the splitters.

Fig. 2 is a plan view of the tool.

Fig. 3 is a side elevation of the same tool looking at the side thereof showing the strippers.

Fig. 4 is an end elevation of the pliers 70 looking toward the jaw end thereof.

Fig. 5 is a perspective view of one of the detached plates having the cutter members.

Fig. 6 shows a slightly modified form of the invention in which the cutter plate is 75 attached to the top of one of the jaws without the requirement of a mortise or a recess therein.

It is one of the primary objects of the present invention to provide an electrician's 80 wire stripping and splitting tool in which the respective means for stripping and splitting the insulation from the wires are disposed in such a manner to afford convenient operation of the tool and also securing 85 rigidity of the parts and to obtain a tool of the maximum strength.

I have found by actual construction of tools of the type involved therein that the maximum strength, rigidity of the parts, 90 simplicity of construction, and economical methods of manufacture may all be readily achieved by employing a few and simple parts as hereinafter shown in the embodiment of the invention illustrated in Figs. 95 1 to 3, wherein I have shown a common and well known form of pliers having a pair of handles 2-3 which are respectively pivoted upon a pivot 4 and provided at the opposite ends with upper and lower or opposed 100 jaws 5 and 6, having meeting faces 7-7. The hubs of the levers are shown at 8. The meeting faces of the jaws are recessed as at 9 and transversely disposed across one side

of the recess and at the side of the jaws 5-6 are arranged side cutters 10-10 in the meeting plane of the jaws 5-6.

In the practical use of the tool a piece of 5 wire may be readily cut in usual manner by transverse insertion between the side cutters 10-10 which are brought together by pressure applied in the usual manner to the handles 2-3.

10 To provide for the ready splitting of a piece of standard twin electrical conducting wire of the type to which the insulation is so applied as to assume a substantially flat longitudinal form or an elliptical cross section as clearly shown at F in Fig. 2, I attach to the upper or outer surface of each of the jaws, a plate of material, which may be suitably hardened to secure durability of the stripping edges, having a transverse or 15 body portion 12 of suitable proportion which may be mortised into the recess 13 provided in the outer surfaces of the jaws, each plate is provided at its end with forwardly projecting arm portions 14 and 15 20 which gives the plate a general U-shaped formation in plan, these arms being adapted to straddle the side faces of the jaws as shown in Fig. 2, the inner edges of the jaws lying closely contiguous to the adjacent 25 faces of the jaws and contacting therewith, so as to prevent the plate 12 from having any play about the screw 16 which when 30 passed through the apertures 17' in the plate 12, fastens the plate to the jaw.

35 One of the arms 14, in Fig. 5, is preferably bent down at an angle substantially equal to the bevel of the outer surface of the end of a jaw 5 for instance, and is also provided on its outer end with a downwardly turned portion 17', the plane of which is parallel to the edge of the arm 14, and is thus parallel and spaced to the side of the plier jaw, the space providing for the 40 passage therebetween of one section of the wire F, Fig. 2. When it is desired to split this form of wire into two sections for any suitable length by simply pulling the pliers longitudinally along the piece of wire F to the desired extent after the jaws 5 and 6 45 have been brought together so that the knife edges 18 of the pair of opposed blades 17 approach each other to cut through the insulation.

For the purpose of providing for the removal of insulation from a piece of wire of the round cross sectional type as shown at R in Fig. 3, the arm 15 of the blade 12, one of which is secured to each of the outer spaces of the jaws 5 and 6 is shown as provided with a downwardly turned portion 22, Fig. 5, and formed with a cutting edge 23, which extends in a plane transverse to the arm 15 and therefore to the adjacent side face of the jaws 5 and 6; the cutting edges 60 of the cutters 23 being disposed in the pincer

plane of the jaws 5 and 6. These stripping blades 23 are provided each with a plurality of notches 24 and 25 of different sizes.

When it is desired to strip a piece of round twin wire an adjusting screw 20 may 70 be turned to the desired position to limit the closing of the jaws and protect the wire core and the handles 2-3 of the plier separated so as to open the cutters 10-10 to the required degree, whereupon the round 75 wire to be stripped may be introduced lengthwise along the cutters 10-10, and these brought together so as to split the outermost insulation. That portion of the insulation lying between the blades 23 is 80 split and as the wire is transversely slid along these blades and across the faces of the jaws 5 and 6, the insulation is further crushed to a degree which may be determined by the adjustment of the screw 20 85 so as to prevent the cutting of the metallic wire.

It is an important feature of the present invention, that the cutting blades 17 and 23, are disposed adjacent to the faces of 90 the jaws 5 and 6 and remote from the pivot 4 and the hubs 8 of the pliers so as to facilitate the cutting of wire of various diameters, this being possible by the degree to which the cutters may be separated from 95 each other by the opening of the handles 2 and 3.

Again, an important feature of the present invention is the rigid and compact disposition of the respective cutter members 17 100 and 23 at opposite sides of jaws 5 and 6 this being possible because of the fact that the pairs of cutters 17-17 and 23-23 are both maintained in close position to the respective sides of the pliers by reason of their 105 being connected to the forwardly extending arms 14 and 15 of the blade 12 which is attached to the plier jaw. This arrangement of the parts, eliminates the tendency of the cutters to spring, which would occur 110 if they were arranged in the relatively remote positions from the side of the plier jaws.

While it is possible to mortise or recess the outer faces of each of the jaws as at 13, 115 to receive the shank 12 of the blade, the latter may be set directly on the outer surface of the jaws as shown in Fig. 6 by means of the screw 16, the desired rigidity of the plate and jaws as to the plier members being obtained by the parallel relation of the arms 14 and 15 to the adjacent side faces of the jaws, the arms frictionally engaging the side faces and thereby preventing any tendency of the plates to play about the fastening 125 16 which may be utilized to attach it.

From the foregoing it will be seen that I have provided a simple, practical and inexpensive tool, whereby both flat and insulated wire and round insulated wire may 130

be handled with facility and insulation quickly split or stripped therefrom and the wire scraped as may be necessary by being introduced into the notches 24 or 25 according to the size of the wire, the scraping being quickly accomplished by simply slipping the wire along the jaws so that the closed blades 23 will cause the notched edges to ride upon the wire, and for preventing the latter from being mutilated, the set screw 20 can be adjusted to prevent excessive removal or cutting of the metal.

It is understood that various details in proportion of the parts and other modifications as for instance, change in the relative position and angularity may be resorted to within the principle of the invention.

What I claim as new is:

1. A pair of splitting and stripping pliers having in combination, jaws with pincer faces, means for controlling the approach of the said faces, and pairs of plates secured to the outer faces of the jaws, each plate having a forwardly extending arm at each end, the ends of the arms having cutting blades bent toward the plane of the respective face of the jaws.

2. A pair of splitting and stripping pliers having in combination, jaws with pincer faces, means for controlling the approach of the said faces, and pairs of plates secured to the outer faces of the jaws, each plate having a forwardly extending arm at each end, bearing against its side of a jaw to prevent turning of the plate, the ends of the arms having cutting blades bent toward the plane of the respective face of the jaws.

3. A pair of splitting and stripping pliers having in combination, jaws with pincer faces, means for controlling the approach of the said faces, and pairs of plates secured to the jaws, each plate having cutting blades bent toward the plane of the respective faces of the jaws, one set of blades disposed transversely to a side of the jaws and the other set disposed in spaced parallel relation thereto.

4. A pair of splitting and stripping pliers having, in combination, pivoted jaws, means for controlling the approach of the jaws, and plates attached transversely to the jaws,

each plate having arms projecting forwardly or away from the jaw pivot and provided with cutting blades bent toward the plane of the respective jaw. 55

5. A pair of splitting and stripping pliers having in combination, pivoted jaws, means for controlling the approach of the jaws, and plates attached transversely to the jaws, each plate having at its ends arms projecting forwardly or away from the jaw pivot and provided with cutting blades bent toward the plane of the respective jaw, the inner edges of the arms lying contiguous to the sides of the jaws. 65

6. Insulation splitting and stripping means for pliers, comprising a pair of plates attachable to the plier jaws, each plate having a transverse body portion with angularly disposed blades respectively for splitting and stripping insulation, said blades disposed perpendicularly to each other. 70

7. Wire-insulation splitting, stripping and cutting pliers, comprising, in combination, pivoted levers having pincer jaws at one end transversely recessed adjacent to the fulcrum and provided with side cutters across the recess, and a set of splitting blades disposed parallel to and spaced from one side of the jaws forward of the recess 80 and a pair of stripping blades disposed perpendicularly to the other side of the jaws.

8. A pair of splitting and stripping pliers having, in combination, jaws with pincer faces, and pairs of plates secured transversely to and projecting beyond the jaws and each having cutting blades bent toward the plane of the pincer face of the respective jaw, the blades on each plate being relatively perpendicular. 85

9. A pair of splitting and stripping pliers having, in combination, jaws with pincer faces, and pairs of plates secured transversely to and projecting beyond the jaws and each having cutting blades bent toward the plane of the pincer face of the respective jaw, the blades on each plate being relatively perpendicular, the stripping blades having notched edges to embrace a wire. 95

In testimony whereof I affix my signature.

SOLOMON E. AARON.
